UNITED STATES PATENT OFFICE.

JOHN C. MEISTER AND JOHN A. COCHRAN, OF STERLING, ILLINOIS.

DESIGN FOR A GAS OR GASOLENE STOVE VENTILATING-CABINET.

SPECIFICATION forming part of Design No. 30,547, dated April 11, 1899.

Application filed February 27, 1899. Serial No. 707,114. Term of patent 14 years.

To all whom it may concern:

Be it known that we, JOHN C. MEISTER and JOHN A. COCHRAN, citizens of the United States, residing in the city of Sterling, county of Whiteside, State of Illinois, have invented and produced a new and original Design for a Gas or Gasoline Stove Ventilating-Cabinet, of which the following is a specification, reference being had to the accompanying drawing, forming part thereof.

The leading features of our design are a flanged floor, a hood, and sides and back connecting the same.

In the drawing, which is a perspective of our design, B' designates the floor, which is rectangular in form and is bordered by the flange B. The sides C have three straight edges, respectively, but the fourth is cut away to form the curve, as shown. The sides C

are set upon the ends of the floor B' at right angles thereto. The hood is composed of the front and side sections E, curved as shown, and of the back A, which is shaped to meet the rear edges of the side sections E, the sides C, and the floor B'. 25

G designates a pipe extension of the hood, and G' the opening in the top of the same.

What we claim is—

The design for a gas or gasoline stove ventilating-cabinet substantially as shown and 30 described.

In testimony whereof we have hereunto set our hands.

JOHN C. MEISTER.
JOHN A. COCHRAN.
